Commonly assigned U.S. Appl. No. 29/526,730, filed May 13, 2015, entitled Seating.

(Continued)

Primary Examiner — Mimosa De(74) *Attorney, Agent, or Firm* — Gardner, Linn, Burkhart & Flory, LLP(57) **CLAIM**

The ornamental design for the seating, substantially as shown and described.

DESCRIPTION

FIG. 1 is a perspective view of seating, according to the present invention;

FIG. 2 is a front elevation view of the seating of FIG. 1; FIG. 3 is a left-side elevation view of the seating of FIG. 1; FIG. 4 is a rear elevation view of the seating of FIG. 1; FIG. 5 is a right-side elevation view of the seating of FIG. 1;

FIG. 6 is a top plan view of the seating of FIG. 1; and, FIG. 7 is a bottom plan view of the seating of FIG. 1. The broken lines shown are included for the purpose of illustrating environment of the design and form no part of the claimed design.
